DESIGN FOR A PORTABLE WARDROBE OR SIMILAR ARTICLE

Alfred P. Kitson, Aptos, Calif.

Application February 19, 1947, Serial No. 137,023

Term of patent 3½ years

(Cl. D87—5)

To all whom it may concern:

Be it known that I, Alfred P. Kitson, a citizen of the United States and resident of the city of Aptos, in the county of Santa Cruz and State of California, have invented a new, original, and ornamental Design for a Portable Wardrobe or Similar Article, of which the following is a specification, reference being had to the accompanying drawings, forming a part thereof.

Fig. 1 is a perspective view of a portable wardrobe or similar article, showing my new design in open position.

Fig. 2 is a rear view of the same.

Fig. 3 is a bottom view of the same.

The characteristic features of the design reside in the outwardly projecting shelf unit in its relationship to and association with the enclosed back unit, all as shown.

I claim:

The ornamental design for a portable wardrobe or similar article, as shown and described.

ALFRED P. KITSON.
